EMBORESSED PAPER NAPKIN

Albert C. Jensen, Milwaukee, Wis., assignor to American Paper & Plastic Products, Inc., Milwaukee, Wis., a corporation of Wisconsin

Filed Oct. 12, 1964, Ser. No. 82,126

Term of patent 14 years

(Cl. D59—2)

FIG. 2

FIG. 1 is a plan view of an embossed paper napkin embodying my new design, the design being shown in full lines only on one-quarter of the face of the napkin, each of the remaining three-quarters of the napkin shown in broken lines bearing the identical design in proper relationship to complete the napkin.

FIG. 2 is a fragmentary detail view on a very enlarged scale showing a cross section taken on line 2—2 of FIG. 1.

I claim:

The ornamental design for an embossed paper napkin, as shown and described.
